UNITED STATES PATENT OFFICE.

OZIA A. ESSIG, OF CANTON, OHIO.

SASH LOCK AND LIFT.

SPECIFICATION forming part of Letters Patent No. 765,172, dated July 19, 1904.

Application filed November 13, 1903. Serial No. 181,084. (No model.)

To all whom it may concern:

Be it known that I, OZIA A. ESSIG, a citizen of the United States, residing at Canton, in the county of Stark and State of Ohio, have invented 5 certain new and useful Improvements in Sash Locks and Lifts; and I do hereby declare that the following is a full, clear, and exact description of the same, reference being had to the annexed drawings, making a part of this 10 specification, and to the figures of reference marked thereon, in which—

Figure 1 is a view showing the sash lock and lift properly applied to a window and the window-sash locked. Fig. 2 is a view showing a 15 portion of a window-sill, also a portion of the window-sash, showing my improved lock properly attached and the lower sash elevated. Fig. 3 is a top view of the socket. Fig. 4 is a front view of the socket, showing the lock-bar locked thereon and illustrating the lock-holding lever extension in section. Fig. 5 is a vertical section showing the window-sash locked.

The present invention has relation to sash 25 lock and lift; and it consists in the novel construction hereinafter described, and particularly pointed out in the claims.

Similar numerals of reference indicate 30 corresponding parts in all the figures of the drawings.

In the accompanying drawings, 1 represents a window-frame, which is of the ordinary construction, and 2 represents the sash, which of course is adapted to move up and down in the usual manner and to which sash is attached the glass.

To the bottom member of the sash-frame 2 is attached the combined lift and lock bar 3, the upper end of which is provided with the 40 lift-flange 4, which lift-flange is substantially of the form shown and is preferably formed integral with the bar. The bottom of the lower end of the bar 3 is provided with the angle portion 5, which angle portion extends 45 forward and at an angle to the vertical face of the lower sash-rail. The front or forward face of the angle portion 5 is provided with the lug 6, the upper portion of which is provided with a smooth flat face 7.

50 The socket-plate 8 is substantially of the

form shown and is secured to the window-sill 9 and placed in such a position that its rear edge will come in a vertical line with the sash-shoulder 10, formed upon the sill 9.

The socket-plate 8 is provided with the forward extension 11, which forward extension is provided with the ridges 12 and 13, located upon opposite sides of the extension 11, the ridge 13 being somewhat higher than the ridge 12, said ridges being formed of different 55 heights for the purpose hereinafter described.

The socket-plate 8 is provided with the openings 14 and 15, the opening 15 entering to and communicating with the opening 14. The opening 14 is for the purpose of receiving the 60 angle extension 5, the opening 15 being for the purpose of receiving the lug 6.

To the socket-plate 8 is pivotally attached the lock-bar 16, which lock-bar is formed of such a length that when it is turned upon its pivot 70 point, so as to become parallel with the extension 11, its inner end will come over the top of the lug 6 when the parts are in the position illustrated in Fig. 5, thereby locking the sash to the window-sill. The lock-bar 16 is provided at its outer end with the downward-extending portion 17, which downward-extending portion is so formed and located that its 75 under edge will press against the ridge 12 as it passes said ridge.

The extension 11 is slightly curved upward, so that its outer end will clear the window-sill, thereby allowing the extension to be sprung downward sufficient to allow the lock-bar to pass the ridge 12, the ridge 13, however, being formed of sufficient height to prevent further rotation of the lock-bar, thereby holding the lock-bar in proper position to lock the sash and at the same time prevent any accidental displacement of the lock-bar. 85 It will be understood that the extension should have slight spring within itself, as the only object is to allow the same to be sprung downward but a trifle, so that the downward-extending portion of the lock-bar 17 will pass 90 the lowermost ridge 12.

In order that the extension 11 may be sprung downward at the time the downward-extended portion 17 of the lock-bar 16 passes 100 the ridge 12, the outer end of the extension

11 is curved upward and its bottom or under side removed from the bottom of the window-sill, as illustrated in Fig. 5, and of course the extension 11 should be formed so that its normal position will be that shown in Fig. 5, and when released after being pressed downward it will resume its natural position. In order to accomplish this result, the extension 11 should be formed of suitable spring material.

10 The socket-plate is provided with the beveled back portion 18, which beveled back portion is provided with the inclined face adapted to engage the angled portion of the bar 3, thereby drawing the sash-rail toward the 15 shoulder 10 of the window-sill 9.

It will be understood that by my peculiar arrangement the sash-frame is held snugly in position when locked, thereby preventing any rattling or movement of the sash and at the 20 same time securely locking the sash in a closed position.

Having fully described my invention, what I claim as new, and desire to secure by Letters Patent, is—

25 1. In a sash lock and lift, a bar secured to the rail of a sash, said bar provided at its lower portion with an angled part, said angle part provided with a lug, a socket-plate secured to a window-sill provided with openings, one of said openings adapted to receive the angle portion of the bar, and the other adapted to receive the lug, a lock-bar pivoted to the socket-plate and adapted to lock the bar in the socket-plate, substantially as and 30 for the purpose specified.

35 2. As an improved article of manufacture, a sash lock and lift consisting of a socket-plate, said socket-plate provided with a spring extension provided with ribs, a lock-bar piv-

40 oted to the socket-plate and adapted to be engaged at its free end between the ribs of the spring extension, and a bar detachable from the socket-plate, substantially as and for the purpose specified.

3. A socket-plate provided with openings, 45 a beveled part located adjacent to the larger opening, a bar provided with a lower angle portion, said bar provided with a lug at its lower end, and a lifting-flange at its upper end, and a lock-bar pivoted to the socket-plate, substantially as and for the purpose specified.

4. In a sash lock and lift, a bar or plate held in fixed position with reference to the window-sash, said bar provided with a lower angled 55 extension, said angle extension inclined forward at its lower end from the face of the sash-rail, and said lower angled extension provided with a lug, a socket-plate provided with a beveled rear portion and a lock-bar pivoted to the 60 socket-plate, and means for holding said lock-bar in fixed position to lock the bar to the socket-plate, substantially as and for the purpose specified.

5. In a sash lock and lift, a bar secured to 65 the sash-rail of the sash, a socket-plate provided with openings to receive the lower portion of the bar, said socket-plate provided with a spring extension, and a lock-bar adapted to be engaged by the spring extension, 70 substantially as and for the purpose specified.

In testimony that I claim the above I have hereunto subscribed my name in the presence of two witnesses.

OZIA A. ESSIG.
